WHEEL CHOCK

Vincent J. Richilano, Lakewood, Ohio, assignor to
Zephyr Industries, Inc., Ashland, Ohio

Filed Sept. 17, 1973, Ser. No. 397,987

Term of patent 14 years

Int. Cl. D12—16

U.S. Cl. D12—217

FIG. 1

FIG. 4

FIG. 2

FIG. 3

FIG. 1 is a perspective view of a wheel chock showing my new design;

FIG. 2 is a rear elevational view thereof;

FIG. 3 is a bottom plan view thereof;

FIG. 4 is a side elevational view thereof;

FIG. 5 is a perspective view of a wheel chock showing a second embodiment of my new design;

FIG. 6 is a rear elevational view of the embodiment shown in FIG. 5;

FIG. 7 is a bottom plan view of the embodiment shown in FIG. 5; and,

FIG. 8 is a side elevational view of the embodiment shown in FIG. 5.

I claim:

The ornamental design for a wheel chock, as shown.
